(57) **CLAIM**

The ornamental design for a lavatory, as shown and described.

DESCRIPTION

In a preferred embodiment, the nature of this product is as a plumbing fixture in the form of a lavatory which is primarily useful for washing the body parts of humans.

FIG. 1 is a right, top, front perspective view of a lavatory embodying my new design;

FIG. 2 is a top plan view thereof;

FIG. 3 is a front elevational view thereof;

FIG. 4 is a right side elevational view thereof, the left side elevational view thereof being a mirror image of the right side shown;

FIG. 5 is a rear elevational view thereof;

FIG. 6 is a bottom plan view thereof;

FIG. 7 is a cross sectional view thereof taken along line 7—7 of FIG. 2;

FIG. 8 is a right, top, front perspective view of a second embodiment of my invention;

FIG. 9 is a top plan view thereof;

FIG. 10 is a front elevational view thereof;

FIG. 11 is a right side elevational view thereof, the left side elevational view thereof being a mirror image of the right side shown;

FIG. 12 is a rear elevational view thereof;

FIG. 13 is a bottom plan view thereof; and,

FIG. 14 is a cross sectional view thereof taken along line 14—14 of FIG. 9.

The broken line representations of drains in FIGS. 1-14 and mounting holes in FIGS. 1, 2, 6, 8, 9 and 13 are for the purpose of illustration only, and form no part of the claimed design.
